CLAIM

The ornamental design for a combined mirror and random selector for a number game, substantially as shown and described.

DESCRIPTION

FIG. 1 is a partial fragmentary front view of a combined mirror and random selector for a number game showing my new design. The broken lines are for illustrative purposes only.

FIG. 2 is a reduced scale side view of the design;

FIG. 3 is a reduced scale rear view of the design;

FIG. 4 is a top view of the design;

FIG. 5 is a bottom view of the design; and

FIG. 6 is a sectional view of the design taken along line 6—6 of FIG. 1.

FIG. 2 FIG. 3

FIG. 4

ANSWER

FIG. 5

FIG. 6
